UNITED STATES PATENT OFFICE.

RUDOLPH G. WINTER, OF MILWAUKEE, WISCONSIN.

VENTILATION WINDOW-LOCK.

1,244,893.

Specification of Letters Patent. Patented Oct. 23, 1917.

Application filed January 7, 1915. Serial No. 1,056.

To all whom it may concern:

Be it known that RUDOLPH G. WINTER, a citizen of the United States of America, residing at Milwaukee, in the county of Milwaukee and State of Wisconsin, has invented 5 a certain new and useful Improvement in Ventilation Window-Locks, of which the following is a specification.

This invention relates to ventilation window locks.

The object of the invention is to afford a ventilation opening or openings by means of a plural sash window, and at the same time secure the sashes firmly together to prevent 15 tampering from the outside. A more specific object of the invention is to provide such a lock of form simple to apply and without defacing or cutting the sash in any way. Another more specific object 20 of the invention is to provide such a lock which will always have its two portions in proper position laterally for engagement, the degree of opening having been adjusted. These and other objects will be clear from 25 a study of the following description and appended claims.

One embodiment of the invention is illustrated in the accompanying drawing, in which the same reference characters denote 30 the same or similar parts.

In the drawing, Figure 1 is a front view of portions of the upper and the lower sashes of a window to which the invention is applied; Fig. 2 is a sectional view of the 35 sashes and lock, taken on line II—II of Fig. 1; and Fig. 3 is a plan view of that portion of the lock which is applicable to the lower sash.

In the drawing, the lower right hand inner portion 1 of the upper sash of a window has attached thereto by means of screws 40 5, 6, a strip 3, of metal formed with transverse recesses 4, 4. These may preferably be formed by corrugating the strip 3. The 45 lower end of strip 3 is so formed as to make up with the lower ledge of the upper sash portion 1, a transverse recess like those formed by corrugating the strip 3.

The upper right hand inner portion 2 of 50 the lower sash of the window has attached thereto a metal plate 8 by means of screws 9. The plate 8 has a rectangular recess formed therein of which the side toward the room is formed with a notch 10. The 55 plate 8 is arched over along a center line at right angles to the window to accommo-

date the reception of a bolt 7 looped to a U-shape intermediate its ends. When in place, the loop of the bolt 7 is just wide enough over all to easily fit between the 60 inner ends of the arches of plate 8, if it is desired to place it in that position, see Fig. 3. The notch 10 is of size sufficient to fit the bolt when retracted thus holding same to indicate that it is retracted and the sash 65 free to be adjusted. The forward end of the bolt is made to be flush with the edge of plate 8 when the bolt 7 is in retracted position. The plate 8 is fastened in such position that the center line of the ends of bolt 7 70 intersects the center line of the strip 3. The diameter of the bolt fits the recesses 4 and also the recess at the lower end of the strip.

In operation, when the window is closed the bolt 7 may be projected into the recess 75 at the lower end of strip 3 to lock the window in that position. The loop of the bolt is swung over to one side or the other to hold the bolt in place. Other ventilating positions may be given the window in the same 80 way by first adjusting the window to the proper height of sash opening. To unlock the window the bolt 7 is swung with its loop in vertical position and then retracted into the notch 10.

It is claimed and desired to secure by Letters Patent.

1. In a lock for windows, the combination of a transversely recessed strip attached to the upper sash with its length extending in the direction of sliding of the sash, a plate attached to the top of the lower sash, and a bolt secured by said plate to slide at right angles to said strip and registrable with the recesses therein, said bolt having a lateral 95 manually operable extension and said plate having on opposite sides of said bolt a formation closely accommodating said extension whereby said bolt may be oscillated to either side when in projected position to 100 positively lock same in such position, and said plate on either side providing a stop for said extension whereby said extension will lie in easily accessible angular positions.

2. In a lock for windows, the combination of a transversely recessed strip attached to the upper sash with its length extending in the direction of sliding of the sash, a plate attached to the top of the lower sash, and a bolt secured by said plate to slide at 105 right angles to said strip and registrable with the recesses therein, said bolt having a

lateral manually operable extension and said plate having an opening therethrough and having opposite portions thereof formed with aligned arches to secure said bolt, said extension projecting through the opening of said plate and fitting closely between the edge walls of said arches when said bolt is oscillated to either side to positively lock same and only when in extended position, and said arch remote from the upper sash having at its top portion a notch whereby when said extension is in vertical position there is play between same and said edge walls and said bolt may be retracted, and held in indicating position.

3. As an article of manufacture, a window lock comprised of a recessed strip adapted to be fastened to the upper sash of a window, a plate adapted to be fastened to the

lower sash and having an oblong opening 20 therein at whose opposite sides are formed arches at the inner edge of one of which is formed a notch, and a bolt having a lateral extension said bolt being slidably securable within said arches by the fixing of said plate in place and said extension laterally swingable in either direction to closely fit within said oblong opening when said bolt is extended into a strip recess to hold same 30 in extended position and entering said notch when said bolt is retracted.

In testimony whereof, the signature of the inventor is affixed hereto in the presence of two witnesses.

RUDOLPH G. WINTER.
